BRAKE

Ludger E. La Brie, South Bend, Ind., assignor to
 Bendix Brake Company, South Bend, Ind., a
 corporation of Illinois

Original application June 20, 1927, Serial No.
 199,988. Divided and this application March 7,
 1931. Serial No. 520,812

8 Claims. (Cl. 188—79.5)

This invention relates to brake operating levers and is illustrated as embodied in an internal expanding brake for motor vehicles.

The present invention is a division of my 5 pending application, filed June 20, 1927, Serial No. 199,988.

An object of the invention is to provide a simple and inexpensive and yet an efficient operating lever for applying the brake.

0 An important feature of novelty relates to a simplified adjusting device for an arm on the cam shaft, although the novelty of this adjustment is not limited to its use on the cam shaft of a brake. Preferably there are three members 5 arranged side by side on a shaft, the outside members being fixed on the shaft and the center member being angularly movable and formed with teeth meshing with an adjusting member supported by the outside members.

20 The outside members are arranged to have wedging engagement with the adjusting member and to be clamped against it under considerable tension by a nut threaded on the end of the shaft and tightened after the adjustment is 25 made, thus providing a strong joint.

Other objects and features of the invention, including various desirable details of structure, will be apparent from the following description of the illustrative embodiment shown in the accompanying drawing, in which:

Figure 1 is a vertical section through the brake just inside the head of the brake drum illustrating the brake shoes in side elevation and showing the invention as applied;

35 Figure 2 is a section substantially on the line 2—2 of Figure 1;

Figure 3 is an enlarged sectional view of the operating lever; and

40 Figure 4 is an elevation showing the adjusting means.

Referring to the drawing for more specific details of the invention, 10 represents a rotatable drum, at the open side of which is arranged a suitable stationary support such as a backing 45 plate 12 and within which is arranged the friction means of the brake comprising a primary shoe 14, a secondary shoe 16, and an auxiliary shoe 18.

The primary shoe 14 is positioned on a steady 50 rest 20 carried by the backing plate. The shoes 14 and 18 are urged inwardly away from the drum toward idle position by a return spring 22 connecting them, and the shoe 16 is urged away from the drum toward idle position by an auxiliary return spring 24 connecting the shoe 14

to the backing plate, and acting on the shoe 16 through a pivot 26 connecting the shoes 14 and 16.

Shoe 16 is anchored at its end on a fixed pivot 28 carried by the backing plate 12 and passing through a relatively large opening 30 in the web of shoe 18, and the shoe 18 is anchored on a fixed pivot 32 also carried by the backing plate 12 and passing through a relatively large opening 34 in the web of shoe 16. The anchors 28 and 32 65 may, if desired, be connected by a reinforcing plate 34.

The idle position of the secondary shoe 16 is preferably determined automatically by an adjustable stop 36 including a steady rest 38 carried by the backing plate 12 and passing through a relatively large opening 40 in the web of the shoe 16, so that it does not interfere with the movement of the shoe.

The brake is arranged to be applied against 75 the resistance of springs 22 and 24 by a suitable applying means, preferably including a pair of applying devices such as cams 42, which may be flat steel stampings having the desired outline, and which engage opposite sides of the ends of 80 the shoes 14 and 18, or their equivalents to prevent lateral movement of the shoes without the provision of any special means such as steady rests. The cams are in operative engagement with thrust devices such as rollers 44 pivotally 85 mounted on opposite sides of the shoes or their equivalents.

Preferably the cams 42, or their equivalents, are operatively connected by a pivot 46 to an arm 48 between the cams and which may be integral with a cam shaft 50 journaled in a bearing 90 on the backing plate 12.

The end of the shaft 50 is provided with a flattened portion 42 upon which are positioned for axial movement two outside members 54 inter- 95 engaging with the flat portion on the shaft, so that they cannot turn angularly on the shaft, and between the outside members 54 is a center member or brake-applying arm 56 angularly movable on the shaft. The member 56 is formed 100 at its upper edge with a segmental portion having teeth 58 meshing with a worm 60 supported by registering grooves 62 and 64 formed in the ends of the members 54. These grooves are so formed that they provide a wedging action on 105 the worm 60 pulling it firmly down against the teeth 58 when a nut 66 threaded on the end of the shaft is tightened up to compress the members 54 against opposite sides of the arm 56. The worm 60 is provided with integral heads 110

68 on its opposite ends for engagement with the sides of the members 54 to prevent endwise movement of the worm, and one of the heads is provided with a diametral slot 70 for the reception of an adjusting tool.

5 While one illustrative embodiment of the invention has been described in detail, it is not my intention to limit its scope to that particular embodiment or otherwise than by the terms of 10 the appended claims.

Having thus described the various features of the invention, what I claim as new and desire to secure by Letters Patent is:

15 1. Brake-applying means comprising a shaft having a flattened portion, an operating arm loosely sleeved on the flattened portion and provided with a toothed segment, an adjusting member meshing with the teeth, and a pair of members inter-engaging the flattened portion of the 20 shaft on opposite sides of the arm and having registering grooves providing a bearing for the adjusting member.

25 2. Operating means for a shaft comprising three members mounted on the shaft side by side, the two outside members being fixed against rotation on the shaft and the center member being rotatable on the shaft and provided with a toothed segment together with an adjusting device meshing with the teeth and engaging the 30 outside members.

35 3. Adjustable mechanism for a shaft having a non-circular portion, comprising two clamping members mounted on the non-circular portion to rotate with the shaft, at least one of the members having limited axial movement toward and away from the other member, an intermediate torque-applying member loosely mounted on said non-circular portion of the shaft between the two clamping members and capable of rotatable adjustment about the shaft, and means 40 carried by and interposed between said two clamping members coupled with the torque-applying member to hold it at adjusted positions upon the shaft.

45 4. Adjustable mechanism for a shaft comprising

ing a pair of members mounted on the shaft to rotate therewith but at least one of which is axially movable thereon, a third member adjustably rotatable upon the shaft between said pair of members, and a part positioned between said pair of members coupled with the third member and operable to adjustably position the same about the shaft.

50 5. Adjustable mechanism for a shaft comprising a pair of clamping members mounted thereon to rotate therewith but movable thereover toward and away from each other, means operable to hold said members together, a torque-applying member rotatably supported on the shaft between the clamping members, and a part rotatably supported between the clamping members and coupled with the torque-applying member to rotatably position the torque-applying member on the shaft.

55 6. Adjustable mechanism for a shaft comprising a torque arm loosely rotatably supported on the shaft, a pair of clamping members fixed on the shaft against rotation upon opposite sides of the arm, adjustable means operable to hold said clamping members toward said arm, and a 100 rotatable screw supported between said clamping members and coupled with the arm to rotatably adjust the same about the shaft.

7. Operating means for a shaft comprising three members mounted on the shaft side by 105 side, the two outside members being fixed against rotation on the shaft and the center member being rotatable on the shaft, and a part carried by said outside members engaging said center member to adjustably and rotatably position the same about the shaft.

8. Operating means for a shaft comprising a plurality of members mounted on the shaft side by side, one being fixed against rotation on the shaft, and another being rotatable on the shaft, 115 and one of said members being provided with a toothed segment, and an adjusting device meshing with the teeth of the segment and engaging the other member.
